CLAIM

The ornamental design for a television set, as shown and described.

DESCRIPTION

FIG. 1 is a front, right perspective view of the television set showing my new design with the display in an unrolled state;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right perspective view of the television set with the display in a rolled state;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a front, right perspective view of the television set shown with a cover over the rolled display; and,

FIG. 16 is an exploded front, right perspective view of the television set shown with the cover separated from the rolled display.
